United States Patent

Des. 238,717

Patented Feb. 3, 1976

238,717

SPHYGMOMANOMETER

Edward Lynn Peart, Arden, and John Bayne Ashe, Ashe-ville, N.C., assignors to Sybron Corporation, Roches-ter, N.Y.

Filed May 3, 1974, Ser. No. 466,694

Term of patent 14 years

Int. Cl. D10—04; D24—02
U.S. Cl. D83—12 R

FIG. 1

FIG. 2

FIG. 3

FIG. 4

FIG. 5

FIG. 1 is a front elevation of a sphygmomanometer showing our new design;

FIG. 2 is a side elevation thereof;

FIG. 3 is a rear elevation thereof;

FIG. 4 is a top plan view thereof; and

FIG. 5 is a bottom plan view thereof.

We claim:

The ornamental design for a sphygmomanometer, as shown and described.
